(57) **CLAIM**

The ornamental design for a transformable desk lamp with five bars, as shown and described.

DESCRIPTION

FIG. 1 is a top perspective view of a transformable desk lamp with five bars, showing my new design in a first position of use;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of the transformable desk lamp with five bars in a second position of use; and,

FIG. 10 is a top perspective view of the transformable desk lamp with five bars in a third position of use.

The broken lines in the drawings depict portions of the transformable desk lamp with five bars, that form no part of the claimed design.

1 Claim, 10 Drawing Sheets
